UNITED STATES PATENT OFFICE.

ALBERT P. LEE, OF CHICAGO, ILLINOIS, ASSIGNOR TO LEE LOADER & BODY CO., OF CHICAGO, ILLINOIS.

DUMPING-HOPPER VEHICLE.

1,262,588.

Specification of Letters Patent.

Patented Apr. 9, 1918.

Application filed March 23, 1917. Serial No. 156,803.

To all whom it may concern:

Be it known that I, ALBERT P. LEE, a citizen of the United States, residing at Chicago, in the county of Cook and State 5 of Illinois, have invented a certain new and useful Improvement in Dumping-Hopper Vehicles, of which the following is a full, clear, concise, and exact description, reference being had to the accompanying drawings, forming a part of this specification.

My invention relates to vehicles having dumping hoppers, and is more particularly concerned with the construction of the hopper itself, as also with the locking means 15 by virtue of which the hopper is held in position when loaded.

My invention relates more particularly to hoppers of the kind which are adapted substantially automatically to roll from a charge 20 carrying to a discharge position, the preferred form of course contemplating this rolling action to both sides of the central position.

In accordance with my invention I utilize a hopper of these general characteristics, and in the specific illustration used herein I have taken the hopper shown in my co-pending application Serial No. 142,419, filed Jan. 15, 1917. In hoppers of this character it has been found that the 30 curvature of the hopper body, or in fact the whole general outline of the hopper body must be maintained in order to have proper coöperation between the hopper and the rail on which it rolls. To this end my 35 invention concerns itself with the specific hopper construction which I will now describe in detail in connection with the accompanying drawings illustrating the same, in which—

Figure 1 is an end view of a vehicle constructed in accordance with my invention;

Fig. 2 is a fragmentary sectional view on line 2—2 of Fig. 1;

Fig. 3 is a sectional view along line 3—3 of Fig. 2 looking toward the left;

Fig. 4 is a sectional view along line 3—3 of Fig. 2 looking toward the right;

Fig. 5 is a transverse sectional view of the hopper and rail;

Fig. 6 is a modified form of the structure shown in Fig. 5, and

Fig. 7 is a detail of construction.

Referring more particularly to Fig. 1, I show a vehicle indicated by the wheels 10, 55 10, having the chassis 11, which chassis

carries rails 12 adapted to support the hopper 13 and on which said hopper rolls. The hopper itself, as more clearly apparent from Figs. 1, 2, 3, 5 and 7 has the channels 14, which are adapted to coöperate with the rail 12. These channels are provided with holes 15 adapted to coöperate with lugs 16 projecting from the rail 12 so as to keep the hopper in its proper position relative to the rails. Across the bottom portion of 65 the channels a tension element 17, shown more clearly in Fig. 7, is provided, which tension element through the agency of its arms 18 is securely riveted at its meeting point with the channel 14 by the rivets 19. 70 This tension element 17 thus prevents flattening of the lower curved portion 20 of the channel 14. By reason of the addition of this tension element the hopper is thus maintained in its original configuration or 75 outline. The hopper structure is then completed through the addition of the sheet metal portion 21 which forms the floor and sides of the hopper, and which is of course of substantial thickness. The hopper is 80 thus made up of this box structure 21 together with the channels 14 and the tension elements 17, there being of course as many channel elements 14 as there are rails 12, there being usually at least two rails per 85 hopper. The rails 12 are supported at their extremities by the arms 22 and these rails likewise carry the locking brackets 23.

In Fig. 6, I show a modified form of the structure shown in Figs. 1, 2, 3, 5 and 7 90 in that the sheet metal body portion 21 of the hopper extends along the entire length of the channel 14. A tension element 17^a is provided which is riveted to the hopper as shown by the bolts 24 and thus serves its 95 purpose of preventing flattening of the hopper bottom. These tension elements 17^a may of course be used for the additional purpose of a support for a false bottom indicated by the boards 25. The boards 25 100 of course may be omitted at times so that the entire hopper may be filled with material, which it is desired to convey.

In order to lock the hopper in its central position I provide a bolt 26 carried upon a stem 27, which stem is mounted in the lugs 28 and 29 carried at the extremity of the hopper. A spring 30 tends to press the stem 27 together with its bolt 26 downwardly through the agency of the collar 31 pro- 110

vided upon the stem 27. The stem is preferably square where it passes through the lug 29 so as to prevent rotation thereof. This bolt coöperates with the recess or notch 32 provided in the block 33 carried by the framework 34. When the bolt is in the position shown in Figs. 2 and 4, the hopper is then held in its central position, as readily apparent. This stem 27 projects 10 downwardly and abuts a vertically movable squared pin 35. This pin 35 is confined in its position by the block 36. This pin 35 has fingers 37, 38 adapted to coöperate respectively with slotted links 39 and 40. 15 These slotted links are carried at extremities of arms 41, 42, carried by the shaft 43. This shaft is rotated through the agency of the handle 44.

Now whenever the handle 44 is rotated 20 to either side of its central position one or the other of the links moves its coöperating pin 37 or 38 upwardly, thereby moving the pin 35 upwardly until its top surface projects above the top of the plate 45, 25 immediately subsequently to which the bolt 26 passes out of the recess 32, whereupon the hopper may roll to its discharge position. It will be understood of course that as soon as the top surface of the pin 35 projects above the top surface of the plate 45 30 that then the stem 27 is then no longer confined by the plate 45, and the bolt 26 having been released, the hopper may roll to the side desired. When the hopper is rolled 35 back to its central position the bolt 26 rides over one or the other of the cam surfaces 46 or 47 until it alines with the recess 32 and snaps into position due to the agency of the spring 30 to thereby hold the hopper 40 in its central position. It will be apparent that a rotation to either side of the central position of the handle 44 will occasion a release of the hopper from its locked position. When the stem 27 moves downwardly upon 45 the alinement of the bolt 26 and recess 32 it pushes the pin 35 downwardly, which thereupon rotates the shaft 43 into its central position with the handle 44 standing vertical.

50 From what has been thus described the nature of my invention will be readily apparent to those skilled in the art.

Having however thus described my invention, what I claim as new and desire to set 55 cure by Letters Patent is:

1. In a device of the character described the combination with a rail, of a hopper adapted to roll on said rail from a charge carrying to a discharge position, said hopper 60 having a rounded bottom to coöperate with said rail whereby said hopper is adapted to roll substantially automatically upon said rail, and a tension element joining the extremities of said rounded portion to prevent flattening thereof due to the weight 65

placed in said hopper, the space below the tension element forming part of the interior of the hopper.

2. In a device of the character described the combination with a rail, of a hopper 70 adapted to roll on said rail from a charge carrying to a discharge position, said hopper having a rounded bottom to coöperate with said rail whereby said hopper is adapted to roll substantially automatically upon said 75 rail, a tension element joining the extremities of said rounded portion to prevent flattening thereof due to the weight placed in said hopper, the space below the tension element forming part of the interior of the 80 hopper, and a rail for said hopper coöperating with said first aforesaid rail, said tension element being secured to said second aforesaid rail.

3. In a device of the character described 85 the combination of a rail, of a hopper adapted to roll on said rail from a charge carrying to a discharge position, means for locking said hopper when in its central position, said means including a bolt, a shaft, and 90 means interposed between said shaft and said bolt whereby a rotation of said shaft in either direction causes the unlocking of said bolt.

4. In a device of the character described 95 the combination with a rail, of a hopper adapted to roll on said rail from a charge carrying to a discharge position, means for locking said hopper when in its central position, said means including a bolt, a shaft, 100 means interposed between said shaft and said bolt whereby a rotation of said shaft in either direction causes the unlocking of said bolt, and means provided with a cam surface with which said bolt coöperates 105 when said hopper is moved toward its central position, to direct said bolt into its locking position.

5. In a device of the character described 110 the combination with a rail, of a hopper adapted to roll on said rail from a charge carrying to a discharge position, means for locking said hopper when in its central position, said means including a bolt, a shaft, 115 and means interposed between said shaft and said bolt whereby a rotation of said shaft in either direction causes the unlocking of said bolt, said means interposed between the shaft and said bolt including a pair of links and a pair of pins, said links having slots with which said pins coöperate. 120

6. In a device of the character described the combination with a rail, of a hopper adapted to roll on said rail from a charge carrying to a discharge position, means for 125 locking said hopper when in its central position, said means including a bolt, a shaft, means interposed between said shaft and said bolt whereby a rotation of said shaft in either direction causes the unlocking of said 130

bolt, and means provided with a cam surface with which said bolt coöperates when said hopper is moved toward its central position to direct said bolt into its locking position, said means interposed between the shaft and said bolt including a pair of links and a pair of pins, said links having slots with which said pins coöperate.

7. In a device of the character described 10 the combination with a rail, of a hopper adapted to roll on said rail from a charge carrying to a discharge position, said hopper having a rounded bottom to coöperate with said rail whereby said hopper is adapted 15 to roll substantially automatically upon

said rail, and a tension element in each end of the hopper, said tension elements each joining the extremities of said rounded portion to prevent flattening thereof due to the weight placed in said hopper, said tension 20 elements being adapted to at times support flooring to thereby convert the hopper into a flat bottom receptacle.

In witness whereof I hereunto subscribe my name this 10th day of March, A. D. 25 1917.

ALBERT P. LEE.
